UNITED STATES PATENT OFFICE.

ALFRED A. JENSEN, OF MERRILL, WISCONSIN.

RAILWAY-TIE AND FASTENER.

1,221,330.

Specification of Letters Patent.

Patented Apr. 3, 1917.

Application filed May 27, 1916. Serial No. 100,245.

To all whom it may concern:

Be it known that I, ALFRED A. JENSEN, a citizen of the United States, residing at Merrill, in the county of Lincoln and State 5 of Wisconsin, have invented certain new and useful Improvements in Railway-Ties and Fasteners; and I do hereby declare the following to be a full, clear, and exact description of the invention, such as will enable 10 others skilled in the art to which it appertains to make and use the same.

The primary object of this invention is to admit of the companion rails of a track being conveniently and expeditiously clamped 15 in position on a tie and positively held against spreading.

Another object of the invention is the provision of a novel type of metallic tie for supporting the rails and novel rail-fastening 20 means which have permanent and slideable connection with the tie and can be readily moved into and out of engagement with the rail.

Other objects will appear and be better 25 understood from that embodiment of my invention of which the following is a specification, reference being had to the accompanying drawing forming a part thereof, in which:

30 Figure 1 is a top plan view of the tie,

Fig. 2 is a side elevation thereof and of the rail-fastening member, showing the latter partly in section,

Fig. 3 is a section taken on the line 3—3 35 of Fig. 2, and

Fig. 4 is a side elevation of a modified form of the tie.

Referring to the drawing in detail, the 40 numeral 1 designates, as an entirety, the preferred form of tie, having its body portion formed of a single blank of metal bent longitudinally upon itself to provide a vertical stem 2, and having the upper edges of the sides of the stem deflected laterally to provide flanges 3. The sides of the tie are spaced from each other, at a point centrally of the tie body, so as to provide a recess 4, and the upper surfaces of the flanges 3 are serrated, as shown at 5.

50 Mounted upon the flanges 3 is an elongated plate 6, which has its under surface serrated, as shown at 7, so as to coöperate with the serrated surface 5 on flanges 3 to serve as means for preventing longitudinal move-

ment of the plate 6 on the flanges 3. The 55 plate 6 is provided with a central opening 8, which registers with the recess 4 and the walls of the opening are beveled, for a purpose which will be hereinafter described. The opposite ends of the plate 8 are bent to 60 provide rail-engaging portions 9, which are adapted to engage over the outer side of the base flange of the rails of the track, designated 11.

Associated with the plate 6, and superposed thereon, is another plate 12. The plate 12 is provided with a longitudinal raised portion 13, formed centrally thereon to provide a housing, and the said plate 12 is provided with slots 14, which register with similar slots formed in the plate 6 and with openings in the flanges 3, for the accommodation of bolts 15, which have nuts 16 turned on their lower ends and adjustable against the under side of the flanges 3.

75 Slidably mounted within the raised portion 13 on the plate 12 is a pair of keys 16. These keys 16 coöperate with the portions 9 on the plate 6 for anchoring the rails 11 in position, and, as shown more particularly in 80 Fig. 2, the outer ends of these fasteners 16 are reduced to provide the flanges 17, which engage over the inner longitudinal edges of the base flanges of the rails 11.

75 The keys or fasteners 16 are moved to operative position by means of a manipulating member 18. This manipulating member 18 includes a triangular shaped base 19 and a threaded stem 20. The base 19 overlies the recess 4 in the tie body, and when the manipulating member is in inoperative position, the base is received by the said recess. When the member 18 is moved upwardly, the inclined sides thereon engage the adjacent ends of the keys 16, so as to move the 90 keys 16 outwardly or in the direction of the rails 11, the inner ends of the keys 16 being beveled to agree with the beveled or inclined sides of the base flange 19. When the manipulating member 18 is in the position 95 shown in Fig. 2 the sides of the base 19 engage the beveled sides of the opening 8 so as to limit the upward movement of the manipulating member, and when the manipulating member is in operative position the 100 stem 20 thereon projects through an opening in the raised portion 13 and has a nut 21 threadedly mounted thereon and adjustable 105

against the raised portion 13 so as to hold the manipulating member 18 in operative position.

The tie shown in Fig. 4 consists of a body 22, formed in the same manner as the body of the tie shown in Fig. 1, and has its upper surface thereof serrated, as shown at 23.

The plate 26 is superposed on the tie body 22 and has its under side serrated to 10 coöperate with serrated surface 23 on the upper surface of the tie body, and the said plate 26 has a longitudinally extending raised portion 27, similar to the raised portion 13 of the plate 12 as shown in Figs. 1 and 2, 15 for the reception of slidable locking keys 28, which are identical with the keys 16 shown in Fig. 2 of the drawing. The walls of the body 22 are spaced from each other, at a medial point, as shown at 29 to provide 20 a central recess for the accommodation of the triangularly shaped base carried by the lower end of the manipulating member 29' similar to the manipulating member 18, shown in Fig. 2, and which manipulating member is adapted, when moved upwardly, to slide the keys 28 outwardly and into engagement with the inner flanges of the rails. The opposite ends of the body 22 are formed to provide the raised portions 25 31, the inner edges of which have extensions 32 formed thereon to engage over the outer longitudinal edges of the base flanges of the rail to hold the rail in operative position.

When it is desired to release the rails 35 from the structure shown in either the preferred or modified form, the nuts on the stems of the manipulating members are removed and the members moved inwardly so as to release the rail-engaging keys. 40 After this operation the said keys are moved in the direction of each other by any suitable tool, so as to release the rails and admit of the same being removed from the tie body.

Copies of this patent may be obtained for five cents each, by addressing the "Commissioner of Patents, Washington, D. C."

Having thus described my invention 45 what I claim as new, is:

1. The combination with a rail tie body having rail engaging members located at the opposite ends thereof, and adapted to engage the outer sides of the rail, a housing 50 interposed between the rail engaging members and having its opposite ends opened and spaced from the rail engaging members, means slidably mounted within the housing and operable through the ends thereof, and adapted when slid in one direction to engage the inner side of the flange of the rail, and means operable within the housing for moving the first mentioned means to operative position. 60

2. The combination with a rail tie body having a central recess therein, and a housing associated with the upper side of the tie body having its interior communicating with the recess, the upper wall thereof provided with an opening registering with the recess of the tie body, the said housing having its opposite ends open, rail engaging members slidably mounted within the housing and operable through the open ends of 70 the housing, means comprising a vertically movable plate having inclined sides adapted when the plate is moved upwardly to engage the rail engaging members and move the members outwardly, the said plate being adapted when moved downwardly to be received by the recess in the tie body, so as to admit of the rail engaging members being moved inwardly, a threaded stem carried by the plate and slidably extending through 75 the opening in the upper wall of the housing, and a nut turned on the stem. 80

In testimony whereof I affix my signature in presence of two witnesses.

ALFRED A. JENSEN.
